TORPEDO COURSE CONTROLLER

Carleton H. Schlesman, Washington, D. C., and Raymond C. Kent, Jr., and Roland G. Daudelin, Silver Spring, Md., assignors to the United States of America as represented by the Secretary of the Navy

Application February 29, 1952, Serial No. 274,268

6 Claims. (Cl. 114—24)

(Granted under Title 35, U. S. Code (1952), sec. 266)

The invention described herein may be manufactured and used by or for the Government of the United States of America for governmental purposes without payment of any royalties thereon or therefor.

The present invention relates to a torpedo course controller and more particularly to an electromechanical unit which is adapted to be incorporated in existing torpedoes to provide a means whereby a torpedo will follow a predetermined course pattern.

The steering of torpedoes is accomplished by means of a gyroscope sending signals to a steering motor which in turn transmits the signals to the rudder. The torpedo will follow a course determined by the position of the top cam plate of the gyroscope. To cause the torpedo to follow a predetermined course pattern it is only necessary to provide a means to rotate the top cam plate of the gyroscope an amount correlative of the desired course angle. The torpedo will turn the desired angle and continue on a straight course until the cam plate of the gyroscope is again rotated. Heretofore torpedoes have been designed which are adapted to follow a course determined by a prescribed initial firing angle. However, if the torpedo fails to make a hit it passes on until it becomes exhausted. The present invention provides a means to cause the torpedo to follow a zigzag pattern crossing and recrossing the line of travel of the target thereby increasing the probability of scoring a hit. Devices of this nature have been provided heretofore, however, such units usually involve substantial modification of existing equipment, are not easily assembled or disassembled and are not adapted to the wide variety of course patterns possible with the present invention.

The invention disclosed herein may be incorporated in existing torpedoes without substantial modification thereof and is adapted to rotate the top cam plate of the torpedo gyroscope according to the desired predetermined angles set on the device. The gyroscope in response thereto actuates the steering motor which functions to turn the torpedo rudder. The course controller includes a lower rotor provided with the plurality of contact strips and contact fingers which are connected through a system of switches to an upper rotor which is also provided with a series of contact strips and adjustable contact fingers. The lower rotor is driven by the torpedo propulsion motor through a reduction gearing. The desired course angles are set by moving the adjustable contact fingers on the upper rotor. A motor adapted to be energized by the contact strips on the upper rotor rotates the top cam plate of the gyroscope thereby transmitting the desired course angle to the rudder. Accordingly, as various contacts on the upper rotor are energized the motor is run for varying lengths of time determined by the angles set by the adjustable contact fingers. In addition to providing a means for setting any desired course angles the present invention includes a means for varying the length of the preliminary run of the torpedo. The preliminary run is the straight course the torpedo follows after assuming

2

the direction determined by the initial firing angle and is generally equal to the distance of the firing ship to the target along the course determined by the firing angle.

The primary object of this invention is the provision of means for causing a torpedo to follow a predetermined course pattern in which after assuming the firing angle and running a prescribed time, the torpedo crosses and recrosses the line of movement of the target.

Another object of this invention is the provision of an electromechanical torpedo course controller in which the initial firing angle, length of preliminary run and course pattern angles may be independently varied to suit any operational requirement.

Still another object of this invention is to provide a means for causing a torpedo to follow a predetermined course pattern in which the top cam plate of the gyroscope is rotated to actuate the steering motor which in turn moves the rudder of the torpedo.

A further object of this invention is the provision of a course controller for a torpedo which is adaptable for use with existing equipment without involving substantial modification thereof.

Other objects and many of the attendant advantages of this invention will be readily appreciated as the same becomes better understood by reference to the following detailed description when considered in connection with the accompanying drawings wherein:

Fig. 1 is a front elevational view of the course controller with parts broken away to show certain details;

Fig. 2 is a side elevation of the device with certain parts broken away;

Fig. 3 is a circuit wiring diagram;

Fig. 4 is a pattern of a torpedo course obtained by use of the present invention; and

Fig. 5 is a diagrammatic view showing the arrangement and relative positions of the contact fingers and contact strips on the upper rotor.

Referring now to Fig. 1 there is shown a shaft 1 which extends from the propulsion motor of the torpedo (not shown) to a gear reduction unit 2 which is in a ratio of approximately 5,000 to 1. Within this gear reduction unit there is provided a clutch (not shown) accessible by means of a screw 3 mounted on the outer face of the gear reduction unit. The output shaft 4 extending from the gear reduction unit is fixedly mounted within a lower rotor 5 and has the outer end thereof journaled within a supporting bracket 6. Mounted on the gear reduction unit and extending upwardly therefrom are supporting plates 7 and 8 on the upper ends of which is mounted top plate 9. Fixedly mounted on the rear face of supporting plate 8 are a reversible motor 11 and a three contact relay 12. Shaft 13 extending from the motor is journaled in top plate 9 and provided with a worm 14 engaging worm wheel 17 which through shaft 16 drives worm 15.

Mounted between supporting plates 7 and 8 is an upper bracket 18 and rotatably mounted between this member and the top plate is a shaft 19 which is provided with gear reduction means 21. The upper gear of this means 20 engages worm 15 whereas the lower gear meshes with the gear 22 fixedly mounted on a shaft 23 journaled within the top plate 9. Bevel gears 24 and 25 transmit rotation of shaft 23 to shaft 26 which is journaled within block 27 mounted on the under side of top plate 9. Shaft 26 extends into engagement with the top cam plate of the gyroscope (not shown). Shaft 23 extends downwardly through the upper bracket 18 and the lower end thereof is suitably journaled within supporting bracket 6. Fixedly mounted on shaft 23 is an upper rotor 28 and it is apparent that energization of motor 11 will cause both rotation of the upper rotor 28 through shaft 23 and

rotation of the top cam plate of the gyroscope through engagement with shaft 26.

The lower rotor 5 is provided with six grooves 29 which extend around the entire periphery thereof within which are mounted contact strips 31-36 which are of varying lengths. The relative positions and lengths of these contact strips are shown in the circuit wiring diagram Fig. 3 in which the rotor is shown in developed form. In this figure for the sake of clarity the grooves 29 have been omitted. Contact strips 31 and 36 are 360° in length extending around the entire periphery of the rotor. Contact strip 32 is a 5° segment and is located at approximately the center of the strip 33 which extends through 160°. Contact strip 35 is also 160° in length and strips 34 and 34a are each 20° segments. It can be seen, therefore, that the combination of the contact strips 33, 34a, 34 and 35 extend around the entire periphery of the rotor 5. Fixed contact fingers are provided for engagement with the contact strips 31-36. An insulated bracket 37, Fig. 1, is mounted on support 7 and on the outer end thereof are securely mounted spring contact fingers 38 and 39 which extend into engagement with contact strips 31 and 32. There is further provided on support 7 an insulated bracket 41 on which are mounted contact fingers 42 to 45 which extend into engagement with contact strips 33 to 36 respectively. Fixedly mounted on the lower rotor 5 is worm wheel 46. Rotatably mounted in the supporting plate 7 is a shaft 47, Fig. 2, on the outer end of which is mounted a worm 48 engaging worm wheel 46. It is apparent therefore that, upon release of the shaft 4 from the gear reduction unit 2 by means of the clutch operated by screw 3, the lower rotor 5 can be rotated by rotation of shaft 47.

The upper rotor 28 is also provided with the series of grooves 49 in which are mounted contact strips 51 to 56. The relative positions and lengths of these strips are shown in Fig. 3. Strips 51 and 52 are 360° rings and strips 53 to 56 are split rings each segment of each ring extending through 175° leaving two non-conducting gaps of 5° spaced 180° apart. Mounted on supporting plate 7 is an insulated bracket 57, Fig. 1, which supports spring contact fingers 58 and 59 which extend into engagement with contact strips 51 and 52 respectively. Rotatably mounted in suitable grooves in the upper rotor are worm wheels 61 to 64 on which are securely mounted insulated brackets which serve to support the contact fingers 65 to 68 engaging contact strips 53 to 56, respectively. In Fig. 2 supporting plate 7 is broken away to show the means for rotating the worm wheels. Suitably supported within plate 7 are shafts 69 to 72 the inner ends of which are provided with worms similar to the worms 73 shown on shaft 72. These worms engage worm wheels 61 to 64, respectively whereby rotation of any of the shafts 69 to 72 will impart rotation to the driven worm wheel and contact finger.

Referring now to the circuit wiring diagram of Fig. 3 it can be seen that a number of internal connections have been provided within the lower and upper rotors. In the lower rotor 5 contact strips 32 and 31 are interconnected and contact strip 36 is provided with conductors leading to contact strips 33, 34 and 35. In the upper rotor 28 one segment of each of contact strips 53 to 56 has been connected internally with contact strip 51 whereas the other segment of contact strips 53 to 56 has been connected internally with contact strip 52. It can be further seen that the direction of rotation of motor 11 will depend upon which of contact strips 51 and 52 is energized since contact fingers 58 and 59 connect with opposite sides of the motor. Relay 12 simultaneously actuates switches 74, 75 and 76 one of which, switch 76, is normally in a closed position whereas switches 74 and 75 are normally in an open position. An electrical source is connected through a hydrostatically controlled inertia switch 77 to contact finger 38 and to switches 74, 75 and 76. Contact fingers 42 to 44 are provided with

direct connection with contact fingers 67, 66 and 65, respectively whereas contact fingers 39, 45 and 68 are provided with leads to switches 74 to 76.

The operation of the presently disclosed torpedo course controller will now be described in connection with a typical pattern shown in Fig. 4. The torpedo upon leaving the firing ship 78 assumes a course determined by the initial firing angle A and follows this course for a length of time determined by the length of the preliminary run. The line of movement of the target is represented by the dashed line, and it is anticipated that the torpedo will strike the target at point R. However, if it fails to score a hit at this point it follows the illustrated pattern, and a hit may be scored at point S or point T. For the purposes of explanation it will be assumed that a torpedo turn in a counterclockwise direction represents a negative angle whereas a turn in a clockwise direction corresponds to a positive angle. In the pattern shown, therefore, angle A equals -60°, angle B equals +60°, angle C equals +30°, angle D equals +30°, angle E equals -30°, and angle F equals -30°.

In setting the course controller for this pattern it is first necessary to determine the length of preliminary run desired. From the known speed of the torpedo and the known speed of rotation of lower rotor 5 the amount necessary to offset contact strip 32 with respect to fixed contact finger 39 to secure the desired preliminary run may be determined since the energization of this contact finger is the controlling factor as will be hereinafter more fully described. Contact strip 32 is offset with respect to contact finger 39 by first releasing the shaft 4 from engagement with the gear reduction unit 2 by operation of the clutch means through screw 3 and by manually rotating the lower rotor 5.

The desired course angles are set on the course controller by rotation of the adjustable contact fingers on the upper rotor 28. When contact fingers 65 to 68 are positioned in the non-conducting gaps of contact strips 53 to 56, they are in a zero position, and positive or negative angles may be set depending upon which segment of the split ring contact strip the finger is rotated onto. The settings of the contact fingers with respect to the contact strips on the upper rotor to obtain the pattern illustrated is shown diagrammatically in Fig. 5. Negative angles are set by moving the contact finger to the left of the zero position onto that segment of the contact strip which connects with contact strip 52, and positive angles are set by moving the contact finger onto that segment of the contact strip which connects with the contact strip 51. In order to secure the pattern illustrated in Fig. 4 the settings of the contact fingers with respect to the contact strips are as illustrated at AA in Fig. 5 in which contact finger 68 is offset 60° with respect to the zero position on the negative angle segment of contact strip 56, contact finger 57 is moved to the zero position with respect to contact strip 55, contact finger 66 is moved 30° onto the positive angle segment of contact strip 54, and contact finger 65 is moved 60° onto the positive angle segment of contact strip 53.

When the torpedo is fired, hydrostatically controlled inertia switch 77 will be closed by the pressure of the water thereagainst and current will be supplied to contact strips 31 and 32 by contact finger 38 and current will be further supplied to switches 74, 75 and 76. Since contact strip 32 has been offset with respect to contact finger 39 to set the preliminary run this finger will not be energized. However, as hereinbefore pointed out, switch 76 is normally closed, hence, the current flows to contact strip 56 through contact finger 68 and, since this finger is offset on the negative angle segment of the contact strip 56, the strip 52 will be energized. Contact finger 59 transmits the current to motor 11 which drives the upper rotor and transmits a signal to the top cam plate of the gyroscope. The motor continues to operate until it has driven the upper rotor to a position wherein

the contact finger 68 rests in the non-conducting gap or zero position of contact strip 56 illustrated in Fig. 5 at BB at which time the circuit is broken and the motor is deenergized. It is apparent that the motor 11 has been energized for a length of time sufficient to drive the upper rotor 28 60° and that a signal correlative of this angle has been transmitted to the top cam plate of the gyroscope.

Since the lower rotor 5 is driven by the propulsion motor of the torpedo through the gear reduction unit it is turning continuously throughout the torpedo run. When the lower rotor rotates to a position wherein contact finger 39 engages strip 32 current is supplied to relay 12 which simultaneously operates the switches to close switches 74 and 75 and to open switch 76. Switch 74 performs the function of supplying current directly from the source to the relay 12 to hold the switches in this position after contact finger 39 has run off contact strip 32. Since switch 76 is held in the open position throughout the remainder of the torpedo run, current is not again supplied to the contact finger 68, and, hence, the initial firing angle A is out of the circuit. Switch 75 functions to supply current through contact finger 45 to strip 36 which through internal connections within rotor 5 energizes contact strips 33, 34, and 35.

Since contact strip 32 is located at the center of contact strip 33, when contact finger 39 engages contact strip 32, contact finger 42 is approximately at the center of contact strip 33. Consequently current is supplied from contact strip 33 through contact finger 42 to contact finger 67 on the upper rotor 28. Due to the rotation of the upper rotor 28 when the initial angle A was set in, contact finger 67 is now located 60° on the positive angle segment of contact strip 55 as shown at BB in Fig. 5. Hence the current flows from contact finger 67 through contact strip 55 to contact strip 51. The motor is then driven in the opposite direction to rotate the upper rotor and transmit a signal to the top cam of the gyroscope and continues to operate until contact finger 67 is located at the zero position of contact strip 55. Hence an angle correlative of the 60° contact finger 67 was offset with respect to contact strip 55 has been transmitted to the top cam plate of the gyroscope. During the time the motor is driving the upper rotor to the zero position the lower rotor is moved only one or two degrees hence contact finger 42 is still on strip 33. The torpedo will continue on a straight course determined by the angle B until contact finger 42 has run off contact strip 33 and contact finger 43 engages strip 34. When contact finger 43 engages contact strip 34 to energize finger 66 on the upper rotor this rotor will be in the position illustrated at CC in Fig. 5 with contact finger 66 offset 30° on the positive angle segment of contact strip 54. Current, therefore, flows from contact finger 66 through contact strip 54 to contact strip 51 to drive the motor and transmit a signal to the gyroscope and rotate the upper rotor until contact finger 66 rests in the zero position of contact strip 54. The torpedo will remain on the course determined by angle C for only a short time due to the relatively short length of the contact strip 34. When contact finger 44 engages contact strip 35, contact finger 65 is offset 30° on the positive angle segment of contact strip 53 as shown at DD, Fig. 5. Hence, the motor is driven through contact strip 51 to drive the upper rotor until contact finger 65 rests in the zero position of contact strip 53 and an angle correlative of the 30° contact finger 65 was offset with respect to its contact strip is transmitted to the top cam plate of the gyroscope. Since the full length of contact strip 35 is utilized as compared with the half length of contact strip 33 first used, the torpedo will continue on a course determined by the angle D for twice as long as it continued on the course determined by the angle B. Continued rotation of the lower rotor 5 causes contact strip 34a to engage contact finger 43 to reenergize contact finger 66 which is now offset 30° on the negative

angle segment of contact strip 54 as shown at EE in Fig. 5. Hence the motor 11 is driven through contact strip 52 to turn the upper rotor 28 to a position wherein contact finger 66 rests in the zero position of contact strip 54 and transmits to the gyroscope an angle correlative of the 30° the contact finger 66 was offset with respect to contact strip 54. The position of the contact fingers with respect to the upper rotor is shown at FF in Fig. 5 after the angle E has been transmitted to the gyroscope. Upon continued rotation of the lower rotor 5 contact finger 42 reengages contact strip 33 to transmit the current to contact finger 67 which is now offset 30° on the negative angle segment of contact strip 55 as shown at FF in Fig. 5. Angle F is now transmitted to the gyroscope and, since the full length of the contact strip 33 is utilized, the torpedo continues on the course determined by angle F for a distance equal to the length of the course determined by the angle D. It will be seen that upon further rotation of the lower rotor 5 and reengagement of contact strip 34 a signal correlative of a positive 30° angle will be transmitted to the gyroscope since the contact finger 66 is offset 30° on the positive angle segment of the contact strip 54 as seen in GG Fig. 5. It is apparent that the pattern illustrated will be continued until the torpedo becomes exhausted. It can be seen therefore that there has been provided a course controller for a torpedo in which the initial firing angle, the length of the preliminary run and the pattern angles may be independently varied to suit any desired operational requirements.

Obviously many modifications and variations of the present invention are possible in the light of the above teachings. It is therefore to be understood that within the scope of the appended claims the invention may be practiced otherwise than as specifically described.

What is claimed as new and desired to be secured by Letters Patent of the United States is:

1. In a torpedo having a cam-controlled gyroscope controlling a steering motor which actuates the rudder, a course controller comprising, means responsive to a predetermined input pattern intelligence for producing a signal correlative to a preset initial firing angle, means responsive to a predetermined programming input for producing electrical control correlative to a preset pattern of sequentially changing steering angles, adjustable means for varying the time interval between the energization of said first and second means correlative with the speed of the torpedo, means for effecting a transfer of control from said first named means to said second named means, and means including an electric motor and gear drive connected thereto for transmitting the electrical control to the control cam of said gyroscope.

2. In a device of the class described for prescribing the course traversed by a torpedo having a gyroscope controlling the steering thereof and a control cam for providing controlled steering intelligence for said gyroscope, adjustable means including a plurality of switch contacts having rotatable contacts and positionally movable contact fingers settable at will to produce switch circuit closures of varying duration correlative to the rate of movement of said torpedo and corresponding to preset course angles determined by the positions of said contact fingers, rotatable means responsive to actuation of a propulsion motor within the torpedo for selectively energizing said contact fingers in predetermined time delayed relation, and means including an electric motor and gear drive for said control cam for transmitting to the gyroscope the signals produced by said adjustable means.

3. In a course controller adapted for use in a torpedo having a gyroscope controlling the steering thereof, in combination, an upper rotor having a plurality of semi-cylindrical contact strips thereon, a plurality of positionally adjustable contact fingers movable at will relative to the length of said contact strips, and disposed for contact with said contact strips, each of said contact

fingers being adapted to be selectively positioned to provide a switch closure control according to a desired course angle, means responsive to actuation of a propulsion motor within said torpedo to selectively energize said contact fingers in time delayed sequence correlative to the speed of said propulsion motor, motor means energized by said upper rotor for a duration determined by the position of the energized contact finger, said motor means being connected through a cam means to drive said upper rotor and transmit a signal to the gyroscope correlative to the preset course angle.

4. In combination with a torpedo having a propulsion motor and a gyroscope controlling the steering thereof, a course controller comprising, a lower rotor provided with a plurality of semi-cylindrical contact strips of varying length and connected to be rotated by the propulsion motor of said torpedo in correlation with movement of the torpedo through a body of water, positionally adjustable contact fingers disclosed for engagement with said contact strips and adapted to be energized by contact therewith whereby said contact fingers are disposed to be sequentially energized when said propulsion motor drives said lower rotor, adjustable means adapted to be selectively energized by said contact fingers and producing control corresponding to preset course angles, and circuit means for connecting said controller to the gyroscope whereby the torpedo will follow a pattern determined by said preset course angles.

5. A course controller intended for use with a torpedo provided with a propulsion motor and gyroscope controlling the steering thereof comprising, a lower rotor provided with a plurality of semi-cylindrical contact strips of varying lengths and adapted for connection to be rotated by the propulsion motor of said torpedo, a plurality of contact fingers respectively disposed for selectable movement with respect to said contact strips in a manner to be energized by engagement therewith whereby said contact strips are sequentially energized according to a predetermined program when said propulsion motor drives said lower rotor, an upper rotor having contact strips thereon, adjustable contact fingers associated with said contact strips, each of said adjustable contact fingers being disposed to be selectively positioned according to a desired course angle, the contact fingers of the upper rotor being so disposed and connected as to be sequentially energized by the contact fingers of said lower rotor, a drive motor, gear means connected to said motor disposed to rotate said upper rotor, thereby

to provide contact closures to transmit programming signals to said gyroscope, means connecting said motor with the contact strips of said upper rotor whereby said motor is rotated in either direction for a duration determined by the position of said adjustable contact fingers and whereby signals correlative of the preset course angles are transmitted to said gyroscope.

6. A course controller for a torpedo having a propulsion motor and a cam controlled gyroscope controlling the steering thereof comprising, an electrical source within the torpedo provided with a hydrostatically controlled inertia switch, a lower rotor adapted to be connected for rotation by said propulsion motor and having a plurality of semi-cylindrical contact strips of varying lengths disposed thereon, said contact strips being energized by said electrical source through said inertia switch, a plurality of contact fingers disposed for selectable movement, settable at will, with respect to said contact strips and adapted to be sequentially energized when the lower rotor is rotated by said propulsion motor, an upper rotor having a plurality of contact strips thereon, a plurality of adjustable contact fingers disposed for presetting desired course angles, each of the contact strips on said upper rotor comprising a split ring each segment thereof extending through 175° thereby providing non-conducting gaps 180° apart, said adjustable contact fingers adapted to be offset with respect to the non-conducting gaps of the contact strips through angles correlative of the desired course angles, a motor connected to rotate said upper rotor and provide positioning control for the cam of the gyroscope, and means for energizing said motor connected to the contact strips on the upper rotor, said adjustable contact strips being connected for sequential energization by the contact strips on said lower rotor whereby said motor is energized for a length of time correlative of the angle the energized adjustable contact finger is offset.
